CLAIM

We claim the ornamental design for a combined sander and polisher attachment for a vacuum cleaner, as shown and described.

DESCRIPTION

FIG. 1 is a perspective view of a combined sander and polisher attachment for a vacuum cleaner showing our new design;

FIG. 2 is a left-side elevational view thereof;

FIG. 3 is a front elevational view thereof;

FIG. 4 is a rear elevational view thereof;

FIG. 5 is a right-side elevational view thereof; and,

FIG. 6 is a top view thereof.

The broken line showing of a battery pack is for the purpose of illustrating portions of the article, and forms no part of the claimed design.
